(57) **CLAIM**

The ornamental design for a utility cart, as shown and described.

DESCRIPTION

The nature and intended use of the utility cart is to provide a lightweight and compact cart for transporting items conveniently.

FIG. 1 is a perspective view of a utility cart showing my new design;

FIG. 2 is a front elevational view;

FIG. 3 is a left side elevational view;

FIG. 4 is a rear elevational view;

FIG. 5 is a right side elevational view;

FIG. 6 is a top plan view;

FIG. 7 is a bottom plan view;

FIG. 8 is an alternate perspective view similar to FIG. 1, shown in a collapsed position; and,

FIG. 9 is an alternate perspective view similar to FIG. 1, shown with an additional shelf.
